UNITED STATES PATENT OFFICE.

WALTER E. HOSCH, OF ST. LOUIS, MISSOURI.

DESIGN FOR A HOUSING FOR MEASURING AND COMPUTING MACHINES.

48,248.

Specification for Design.

Patented Dec. 7, 1915.

Application filed September 13, 1915. Serial No. 50,523. Term of patent 14 years.

To all whom it may concern:

Be it known that I, WALTER E. HOSCH, a citizen of the United States, residing at the city of St. Louis, State of Missouri, have invented a new, original, and ornamental Design for a Housing for Measuring and Computing Machines, of which the following is a specification, reference being had to the accompanying drawing, forming part thereof.

The figure is a perspective view of a meas-

uring and computing machine housing showing my new design.

I claim:

The ornamental design for a housing for measuring and computing machines, as shown.

WALTER E. HOSCH.
